UNITED STATES PATENT OFFICE.

HENRY G. KUCK, OF PEORIA, ILLINOIS, ASSIGNOR TO STUBER & KUCK CO., OF PEORIA, ILLINOIS, A CORPORATION OF ILLINOIS.

DISPLAY COVER FOR CONTAINERS.

Application filed September 30, 1922. Serial No. 591,818.

This invention has reference to display-covers for containers and like receptacles in which are packed cakes, crackers and similar pastry and bakery goods.

5 In the handling of crackers and cakes, it has become the custom to ship such articles to the retailers in containers or receptacles, either of tin or fiber-board or other non-metallic, relatively rigid light material, and to 10 supply the dispenser of such articles with display-covers provided with a hinged cover or lid having a transparent opening through which the articles may be viewed and also having strips containing the name of the 15 manufacturer of the articles and the name of the articles contained within such containers or receptacles.

In some instances the container or receptacle, if made of tin, has a removable lid 20 or cover to be replaced by a display-cover, or a hinged cover or lid adapted to be swung back against the container and a display-cover attached over the open end or side of said container. In other instances, 25 where the container is made of fiber-board or other non-metallic material, one end or side is removable to be replaced by a display-cover. The tendency is to reduce the cost of dispensing articles of the character referred to and therefore a cheap and inexpensive container is desirable with a small 30 supply of display-covers capable of attachment to different containers and provided with removable name strips to permit substitution one for another to accommodate 35 the display-covers to containers containing different kinds of articles.

One of the objects of the present invention is to provide a metal display-cover comprising a frame having a stiffening member 40 which also constitutes one of the hinge elements for the hinged cover or lid for said display-cover.

A further object of the invention is to 45 provide a hinged cover or lid for a display-cover having preferably three panels; one a transparent closure for the display of the articles; and the other two comprising name strips and a new and novel means for securing such panel in place and for removably holding such name strips in place.

The invention has for a further object to 50 provide a display-cover arranged for attachment to the open end or side of a container made of metal and also attachable to

the open end or side of a container made of fiber-board or other non-metallic relatively rigid light material; means being employed for fastening said display-cover to a fiber-board or non-metallic container to prevent 60 its flopping off of the container when the hinged cover or lid of the display-cover is swung back to open position. Such fastening means being capable of being used when the display-cover is attached to a metallic 65 container, if so desired.

That the invention may be more fully understood, reference is had to the accompanying drawings forming part of the present description, illustrating a preferred embodiment of the invention, in which:

Figure 1 is a face view of a display-cover embodying my invention, the name strips being omitted;

Figure 2 is an end view of Figure 1, except that the display-cover is shown attached to a container shown in dotted lines;

Figure 3 is a side view of one side of the display-cover shown in Figure 1, and a part of a container shown in dotted lines;

Figure 4 is a view of the display-cover showing the end opposite to that illustrated in Figure 2, a part of a container being shown in dotted lines;

Figure 5 is a view somewhat similar to Figure 1 and partly in section, as the same would appear, if taken on the line 5—5 Figure 3 and illustrates how the name plates are inserted and held, and also the glass panel holding means;

Figure 6 is an enlarged sectional detail as the same would appear if taken on the line 6—6 Figure 1, and illustrates the attachment of the display-cover to a container made of fiber-board or other non-metallic relatively rigid light material and a fastening means to prevent flopping of the display-cover when its hinged cover or lid is swung back and opened;

Figure 7 shows a modified fastening means capable of being used on containers made either of metal or fiber-board;

Figure 8 is a rear or inside face view of the hinged cover or lid for the display-cover and illustrates means for securing a glass panel in place;

Figure 9 is an edge view of one edge of the cover or lid shown in Figure 8;

Figure 10 is a partial plan of the base frame of the display-cover and the stiffen-

90

95

100

105

110

ing member which also constitutes one of the hinge members;

Figure 11 is an edge view of one edge of the frame shown in Figure 10;

5 Figure 12 is a partial face view of the hinged cover or lid for the display-cover and showing how a permanent name strip may be embossed or impressed in the same;

10 Figure 13 is a detail perspective view of a wall of the display-cover frame shown stamped or embossed to receive a wedge shaped locking element adapted to frictionally engage a side wall of the container for fastening the display-cover thereon;

15 Figure 14 is a perspective view of a wedge shaped locking member;

Figure 15 is a detail perspective view of the wall of the display-cover opposite the wall constructed as shown in Figure 13, the 20 same being provided with prongs or teeth to engage a wall of the container when the wedge shown in Figure 14 is used, and

25 Figure 16 is a detail perspective view illustrating a form of yielding grip adapted to engage a wall of the container to frictionally hold the display-cover in place on the container.

Like characters of reference denote corresponding parts throughout the figures.

30 The display-cover includes a preferably rectangular base frame 1 and a cover or lid 2 hinged thereto. The construction of said base frame is best seen in Figures 6, 10 and 11 the same being made of strip tin or other 35 light sheet metal. The side walls 3 may be of suitable depth with the lower edges turned inwardly and back against the sides, as at 4 to stiffen such edges, and the top of the base is formed into a contracted neck 5 by bending the side walls 3 inwardly, as at 40 6 and outwardly, as at 7 with the edges of the latter curled, as at 8 and preferably around a wire 9 forming a stiffening member for the edge of such frame around the 45 mouth thereof, and also to provide one member of the hinge for the hinged cover or lid, as will be explained. The base frame 1 is preferably made rectangular in cross-section to conform to the shape of the standard containers or receptacles, both of metal and fiber-board, although it will be understood such frame could be made round or other desirable shape. Further, such base frame is attachable to the open end or side 50 55 of a container by slipping the same thereover, the side walls 3 embracing the walls of the container, as shown in dotted lines in Figures 2, 3 and 4 and in full lines in Figure 6. For convenience the container is designated A. In Figure 6 the container is 60 preferably shown as made of fiber-board or other non-metallic, relatively rigid light material.

One side wall 3 of the base frame 1, and 65 what may be termed the top wall thereof,

see Figure 2, is cut away, as at 10 for the greater portion of its length leaving the skeleton opposite end flanges 11. Such design of base frame will accommodate itself to metallic containers provided with a 70 hinged lid adapted to be folded back against itself, the flanges 11 being adapted to be passed down between the hinged lid and a wall of the container. Such a practice is well known and need not be further illustrated or described.

The base frame 1 being adaptable to metallic as well as fiber-board containers and because such fiber-board containers are more or less of a flexible character and to prevent the base frame flopping off of the container when the hinged lid or cover 2 is swung

open and to insure the base frame adhering to and embracing the walls of the container, I provide a fastening means which I will now describe. One or more of the side walls 3 of the base frame 1 have a perforation or opening 12 therein through which an ordinary paper fastener 13 may be inserted

80 and then caused to pass through an opening in a wall of the container and the prongs of the fastener bent back against the inside of the container wall, see Figure 6. To remove the display-cover to attach it to another container it is a simple matter to release the fastener or fasteners. In practice

85 only one fastener is necessary, applied as shown in Figure 6 to that side of the display-cover from which and toward which the lid or cover 2 swings. While a fastening means is not considered necessary when the display-cover is applied to a metallic container such could be used, if desirable.

90 In Figure 7 one modified form of fastener is shown, and comprises a nail 14 inserted diagonally across a corner of the base frame through openings 15 in adjoined walls 3 and through adjoined walls of the container A, as shown.

95 In Figure 8 another modified form of fastener is shown, and comprises a nail 14 inserted diagonally across a corner of the base frame through openings 15 in adjoined walls 3 and through adjoined walls of the container A, as shown.

100 Whatever form the fastener takes, it is 110 desirable, due to the interchangeability of the display-covers to containers made of different materials and which may vary slightly in size, and if there is any play between the metal base frame and the fiber-board container some fastening means is essential to either take up such play or insure the elements being fastened or secured.

115 In Figures 13 to 16 further modified fastening means are shown. In Figure 13 the side wall 3 is shown provided with an opening or slot 16 formed by stamping and at the same time embossing a wedge shaped pocket 17 therein. When the base frame has been applied to a container a suitable wedge member 18, see Figure 14, is driven down into the pocket 17, in the opening or slot 16 and the tapered edge 19 of the member 18 caused to frictionally impinge with the surface of the container wall and draw the op-

posite wall 3 of the display-cover into engagement with the wall of the container. In this connection, if it is desired the inturned stiffening edge 4 on the wall 3 opposite that 5 embossed, as at 17, may be provided with prongs or teeth 20, see Figure 15, to penetrate the fiber-board of the container when the wedge member 18, or other suitable fastening means is employed.

10 In Figure 16 a very simple yet effective securing means is shown which may or may not be employed in connection with the features illustrated in Figures 13 and 14. This modification consists in providing spaced 15 slots 21 in a wall 3 of the display-cover and to provide a yielding or spring strip 22 inserted therethrough in the manner shown in Figure 16, which will have an impinging relation with the wall of the container and 20 serve to frictionally hold the base-frame from dislodgement on the container; the beveled or turned over ends preventing the strip from slipping through the slots.

On the hinge side of the base frame 1 25 the wall 7 of the contracted mouth is preferably cut away at points 24, exposing the rod 9 for short distances which serve as hinge elements to be engaged by other hinge elements, to be described, on the lid or 30 cover 2.

The lid or cover 2 for the display-cover is best seen in Figures 5, 8 and 9, although well illustrated in Figures 1, 3 and 6. It 35 preferably includes a face plate 25 formed with inturned flanges 26 on all its four sides, three of which are curled at their inner edges at 27 around a stiffening rod 28. One of such flanges 26 constitutes the hinge side of the lid or cover 2 and it has the spaced curled 40 or inturned portions 29, see Figures 5, 8 and 9, adapted to embrace the rod 9 on the base frame 1 and complete the hinge structure. The elements 29 on the lid or cover 1 are so positioned as to engage the rod 9 and fit in 45 the cut away portions 24 on the base frame, as will be understood. Opposite flanges 26, preferably those at the hinge side and the side opposite thereto are stamped, pressed or otherwise formed with arc shaped seats 30 to receive fastening means for holding a pane of glass.

The face plate 25 of the lid or cover 2 is provided with an enlarged opening 31 therein, and such plate surrounding said opening 55 is suitably embossed, as at 32 to stiffen the said plate. This opening is adapted to be covered by a pane of glass 33 placed within said lid or cover, see Figure 8, and makes it possible to expose to view the contents of a 60 container, while at the same time keeping out dust and dirt. Such pane is removable and is detachably held in place by means of a pair of bowed rods 34, the ends of which 65 are crank shaped, as at 35, and have a bearing in openings 36 in the top and bottom

walls 3 of the base frame 1. To release the pane the rods are swung from locking position, shown in full lines in Figures 5 and 8 to the dotted line position, shown in Figure 8, when the pane may be easily and 70 quickly removed. When the rods 34 are in pane locking position they are swung down against the pane and pressed into the seats 30 in the flanges 26, as shown in Figures 5 and 8; the pane being held against endwise 75 movement in one direction by a flange 26 and in the other direction by a shoulder 37 on the rods 34, see Figure 8.

Said face plate 35 above the opening 31 is stamped, pressed or otherwise suitably 80 formed with preferably oblong panels 38 and 39 extending cross-wise of the plate and strengthened by embossing ribs 40 surrounding the same. The panel 38 is preferably shorter than the panel 39. Each panel at 85 opposite ends is provided with an opening 41 through the plate, and said panels midway their ends are preferably provided with oppositely spaced lips 42 cut from the panel. Also, the face plate beyond the end of the 90 shorter panel 38 and at the hinge side of the lid or cover 2 is provided with a stop 43 cut from the plate so as to project from the inside of said face plate.

Each panel 38 and 39 is adapted to be 95 faced or covered with a name strip 44, which are inserted from the inside of the lid or cover through an opening 41 at one end, slid across the panel lengthwise thereof and under the lips 42 and thence through the opening 41 at the opposite end of the panel. The manner of inserting such name plates is illustrated in Figure 5. The strip 44 for the panel 38 being short requires no slot in a flange 26 to enable it to be placed, as shown 100 in Figure 5, but the strip 44 for the longer panel requires a slot 45 in a flange 26 of the lid or cover to make it possible to insert the strip in place. The shorter strip 44 may have the name of the article to be displayed 105 embossed therein, or the name may appear on a label pasted on the strip. The longer strip may have the name of the manufacturer of the articles displayed, appear thereon in manner similar to the name on the shorter strip, all of which it is believed will 110 be understood. The strip 44 for the shorter panel 38 is limited in its inward movement by the stop 43 and is prevented from sliding out of place, by said stop, when the lid or 115 cover 2 is swung up and back.

In Figure 12, instead of using the upper name strip 44, as shown in Figure 5, a full panel 45 may be impressed in the face plate 25 and the name desired stamped or embossed therein or thereon, or a label with the name appearing thereon pasted thereon.

It will be apparent that various changes may be made in the form, construction and arrangement of parts without departing 130

from the spirit and scope of the invention or sacrificing any of its material advantages, the form herein disclosed being merely a preferred embodiment thereof.

5 What I claim is:—

A display-cover for containers, including a base frame and a lid or cover hinged thereto, said lid or cover having a display opening and seats in opposite side walls of the 10 lid or cover, a transparent cover for said opening, a pair of bowed rods to hold said

transparent cover in place, said rods having crank ends journaled in opposite end walls of the lid or cover and adapted mediate their ends to have a locking relation in the 15 seats in said lid or cover, and also provided with shoulder portions to engage an edge of said transparent cover to prevent endwise movement of the latter.

In witness whereof, I have hereunto affixed 20 my hand this 28th day of September, 1922.

HENRY G. KUCK.
